US00D436982S

(12) **United States Design Patent** (10) Patent No.: **US D436,982 S**
Jannard et al. (45) Date of Patent: ** Jan. 30, 2001

(54) **EYEGLASSES**

- (75) Inventors: **James H. Jannard**, Eastsound, WA (US); **Peter K. Yee**, Irvine, CA (US)
- (73) Assignee: **Oakley, Inc.**, Foothill Ranch, CA (US)
- (**) Term: **14 Years**
- (21) Appl. No.: **29/072,548**
- (22) Filed: **Jun. 24, 1997**

Related U.S. Application Data

- (62) Division of application No. 29/052,338, filed on Mar. 27, 1996.
- (51) **LOC (7) Cl.** **16-06**
- (52) **U.S. Cl.** **D16/326**

(57) **CLAIM**

The ornamental design for eyeglasses, as shown and described.

DESCRIPTION

- FIG. 1 is a front perspective view of the eyeglasses of the present invention;
FIG. 2 is a top plan view of the eyeglasses of FIG. 1;
FIG. 3 is a front elevational view of the eyeglasses of FIG. 1;
FIG. 4 is a right side elevational view of the eyeglasses of FIG. 1, the left side elevational view being a mirror image thereof;
FIG. 5 is a bottom plan view of the eyeglasses of FIG. 1; and,
FIG. 6 is a rear elevational view of the eyeglasses of FIG. 1. Phantom lining, where utilized, is for illustrative purposes only and is not intended to limit the claimed component designs to the features shown in phantom.
